CLAIM

The ornamental design for a hammer, as shown and described.

DESCRIPTION

FIG. 1 is a front perspective view of a hammer showing our design;

FIG. 2 is a left side elevational view, the right side elevational view being a mirror image thereof;

FIG. 3 is a front elevational view;

FIG. 4 is a rear elevational view;

FIG. 5 is a top plan view; and,

FIG. 6 is a bottom plan view.

The broken line portions of the disclosure are for illustrative purposes only and form no part of the claimed design.
